UNITED STATES PATENT OFFICE.

THOMAS MCCOUBRAY, OF NEW YORK, N. Y.

TELEPHONE-TRANSMITTER.

SPECIFICATION forming part of Letters Patent No. 527,214, dated October 9, 1894.

Application filed August 16, 1894. Serial No. 520,544. (No model.)

To all whom it may concern:

Be it known that I, THOMAS MCCOUBRAY, a citizen of the United States, residing at New York, in the county of New York and State of New York, have made a new and useful Invention in Telephonic Transmitters, of which the following is a specification.

My invention is directed particularly to improvements in telephonic transmitters of the Hunnings type in which carbon or equivalent comminuted material is used, and it has for its objects, first, the prevention, as far as possible, of the packing of the powder when in use; second, the accurate adjustment of the parts for the purpose of obtaining the best possible effects, and, third, the accomplishment of any and all results necessarily attributable to the apparatus herein-after described, the essentially novel features of which are particularly pointed out in the claims at the end of this specification.

Referring now to the drawings in detail in all of which like letters of reference represent like parts wherever used, Figure 1 is a sectional view of my improved form of transmitter taken through the body of the instrument. Figs. 2 and 3 are plan views from opposite sides of the metallic plates which hold the comminuted or powdered conducting material between them, and Fig. 4 is a sectional view of a modified form of the apparatus.

B represents the transmitter box and A the mouthpiece secured by screw threads in the usual manner to the box and holding the diaphragm D firmly in position. This diaphragm is of any preferred material and is provided at its center with an opening through which the electrode proper is supported, said electrode consisting of comminuted carbon or equivalent powder C which is held in a cylindrical cup G by metallic or other yielding disks F F'. This cup G is supported by a ring R and a stirrup E, the sustaining end of which projects through the diaphragm and is screw threaded for the reception of a nut n as clearly shown in Fig. 1 of the drawings.

s is an adjusting screw extending through the sustaining portion of the stirrup and having frictional bearing against the central portion of the disk F.

w and w' are conductors running to the battery and usual circuit connections.

On examination of Figs. 2 and 3, it will be seen that the disks F and F' are corrugated spirally and that said spiral corrugations are oppositely disposed so that when placed face to face in the manner shown in Figs. 1 and 4, they will rest upon the powder C in such way that when it tends to move in one direction by reason of its bearing upon the inner face of the disk F, it will have an equal tendency to move in a reverse direction by reason of its bearing upon the disk F', thus causing said powder to always maintain an equal distribution without any tendency to pack, a feature which is very objectionable in transmitters of the Hunnings type.

By turning the adjustment screws in either direction the necessary adjustment is effected.

In the modified form shown in Fig. 4, a projecting pin e is sustained at the rear side of the stirrup E with its free end in mechanical connection with the central portion of the disk F', the adjustment screws acting as before on the disk F.

Having thus described my invention, what I claim, and desire to secure by Letters Patent of the United States, is—

1. A telephonic transmitter having an electrode of comminuted or powdered conducting material sustained between a pair of conducting disks and a ring or cup which in turn is wholly sustained by a stirrup secured to the diaphragm.

2. A telephonic transmitter having an electrode of comminuted or powdered conducting material sustained in a confined position by a stirrup which in turn is secured to the diaphragm.

3. A telephonic transmitter having an electrode of comminuted or powdered conducting material sustained in a confined position by a stirrup which in turn is secured to the diaphragm, in combination with additional means carried also by the diaphragm for effecting an adjustment of the electrode.

4. A telephonic transmitter provided with comminuted or powdered conducting material held in place by two disks having spirally corrugated surfaces.

5. A telephonic transmitter provided with comminuted or powdered conducting material held in place by two disks having spirally

corrugated surfaces, the spirals of which are oppositely disposed.

6. A telephonic transmitter having an electrode of comminuted or powdered conducting material sustained between a pair of conducting disks surrounded by a cup or ring which in turn is wholly sustained by a stirrup detachably secured to the diaphragm.

7. A telephonic transmitter having an electrode of comminuted or powdered conducting material sustained between a pair of conducting disks surrounded by a cup or ring which in turn is wholly sustained by a stirrup detachably secured to the diaphragm, in combination with an adjusting screw extending through the diaphragm and the stirrup and into mechanical contact with one of the disks, substantially as described.

8. A telephonic transmitter having an electrode of comminuted or powdered conducting material held between a pair of conducting disks surrounded by a ring or cup secured to a stirrup which in turn is wholly

sustained at a point near the center of the diaphragm, in combination with an adjusting screw extending through the stirrup and into mechanical contact with one of the disks, substantially as described.

9. A telephonic transmitter having an electrode of comminuted or powdered conducting material held in place by a pair of conducting disks surrounded by a cup or ring detachably secured by a stirrup which in turn is detachably secured to the diaphragm, in combination with an adjusting screw extending through the diaphragm and the stirrup and having mechanical connection with one of the disks.

In testimony whereof I have hereunto subscribed my name this 14th day of August, 1894.

THOMAS MCCOUBRAY.
